UNITED STATES PATENT OFFICE.

PATRICK H. FRIEL, OF KENOSHA, WISCONSIN; HATTIE D. FRIEL, ADMINISTRATRIX OF
SAID PATRICK H. FRIEL, DECEASED, ASSIGNOR TO SIMMONS COMPANY, OF KENOSHA,
WISCONSIN, A CORPORATION OF DELAWARE.

TUBE-DRAWING APPARATUS.

1,321,729.

Specification of Letters Patent. Patented Nov. 11, 1919.

Application filed August 28, 1916, Serial No. 117,386. Renewed May 15, 1919. Serial No. 297,437.

To all whom it may concern:

Be it known that I, PATRICK H. FRIEL, a citizen of the United States, residing at Kenosha, in the county of Kenosha and State of Wisconsin, have invented a certain new and useful Improvement in Tube-Drawing Apparatus, of which the following is a full, clear, concise, and exact description, reference being had to the accompanying drawings, forming a part of this specification.

This invention relates to mechanism for drawing articles, such for instance as hollow tubing, from a source of materials and a machine, forming no part of this invention, initially forming the article to be drawn. The object of the invention is to provide an apparatus for taking hold of the tube or other similar article as it leaves the above mentioned manufacturing machine, and securely gripping it so that it can be drawn out in the ordinary manner into the tube or other desired finished article.

The invention consists in a device of relatively few parts; which can be easily and cheaply made; which is simple in operation, and not liable to get out of order; adapted to successively grip successive parts of the drawn tube or other article whereby such tube may be drawn continuously to any length from the manufacturing machine and under a substantially uniform tension at all times, thus insuring a good finished product. More particularly the invention consists in many features and details of construction which will be hereafter more fully set forth in the specification and claims.

Referring to the drawings, in which similar numerals indicate the same parts throughout the several views,

Figure 1 is a side elevation partially in section of mechanism illustrating this invention in its preferred form, in the act of drawing a tube.

Fig. 2 is a plan view of the mechanism shown in Fig. 1, the tube being omitted to facilitate illustration.

Fig. 3 is an enlarged sectional detail end view on the irregular line 3-3 of Fig. 2.

Fig. 4 is a central enlarged view taken on the line 4-4 of Fig. 3, and on the line 4-4 of Fig. 5.

Fig. 5 is a sectional end view on the line

5-5 of Fig. 4, showing the tube gripping jaws closed.

Fig. 6 is a changed position view of the parts shown in Fig. 5, showing the gripping jaws open.

Fig. 7 is a perspective view of a gripping jaw, and its spring removed from other parts.

Fig. 8 is a perspective view of a removable lining for a gripping jaw adapted to be inserted in the device of Fig. 7 to enable it to handle a tube of a smaller size.

Fig. 9 is a perspective view of certain parts of the drive chain showing particularly the construction of link designed to facilitate positive driving of the gripping jaws.

Fig. 10 is a section on line 10-10 of Fig. 1.

The preferred form of machine illustrated in the drawings is supported upon upright standards 20 spaced apart by any suitable rigid members not interfering with the operative parts of the machine, and particularly by the channel irons 22 spaced apart as shown in Fig. 3 to receive the specially formed U-shaped girder 24 having in its upper surface a track 26 within which the enlarged primary link ends 28 of the primary chain links 30 slide. Journaled in the end standards 20, heretofore described, are shafts 32 and 33, the latter driven by any suitable source of power. Each such shaft carries a sprocket wheel 34, provided in the ordinary manner with teeth 36 adapted to mesh with the primary links 30 of the chain, to be hereafter more fully described, and propel it so that the upper portion of the chain travels from right to left along the track 26 when the machine is viewed in Fig. 1.

The chain is made up of pairs of primary links 30, heretofore described, placed side by side and provided with suitable pivot pins 38 in their opposite ends in the ordinary manner. Between each successive pair of primary links and journaled on such pivot pins 38 is an intermediate link 40, shown in great detail in Fig. 9.

Each of these intermediate links 40 is in its lower half of ordinary construction. The upper half of each such intermediate link is preferably specially formed as shown

in Fig. 9 so as to provide two upwardly rising blocks or lugs 44 and 46, each being of sufficient height to provide openings therein marked respectively 48 and 50 through which the hinge pin 52 of the gripping jaws, to be hereafter described, may pass. The block or lug 46 is substantially higher than is required merely to provide sufficient bearing for such hinge pin, thus providing a bearing surface 54 of substantial size against which the gripping jaws or parts thereof may take bearing and be supported when the fully equipped chain is moved to the right, as viewed in Fig. 9.

Pivoted on the hinge pin 52, which, as above indicated, is inserted through the parts 44 and 46 of each link 40, and between such blocks 44 and 46 are a pair of hinge arms 56 terminating at their outer ends in clamping jaws 60, clearly shown in perspective in Fig. 7. The hinge pins 52 are disposed lengthwise of the chain whereby the jaws 60 swing transversely to the plane or line of travel of the chain and about a common center or axis of swinging movement. Each pair of clamping jaws 60 preferably interfit together, as is clearly shown in Fig. 5, and each such jaw 60 is recessed in the semi-circular line 62 whose center of curvature is at 64. The center of curvature just described lies in the plane of contact 66 between the adjacent jaws 60, which plane also includes the center of pivot pin 52, heretofore described, the result being that when a tube 70 or other article to be worked upon is placed in position, shown in Figs. 5 and 6, the jaws 60 may be freely moved backward and forward between the positions in which they appear in Figs. 5 and 6 without, in any position, interfering with the tube or having their movement interfered with by the tube.

In order to enable the machine to take care of and handle tubes or other articles of different sizes, the jaws 60 may be provided with a series of removable linings 72 having curved interior faces 62^a designed to fit the varied product, such linings being securable in position by any suitable means, as for instance a curved band 74 adapted to fit into a circumferential recess 76 in the surface 62 of a clamping jaw, and be secured in position by any suitable means, such for instance as a screw-threaded stud 78 passing through a hole 80 in the block 60, and permanently attached by a suitable nut 82. When it is desired to draw large tubes, the jaws or blocks 60 will be used without any such lining members 72. When it is desired to draw smaller tubes, lining members 72, one for each jaw 60, provided with the desired curved openings 62^a, will be detachably secured in position, as just described.

The jaws 60 are preferably urged from

the position of Fig. 5 toward the open position of Fig. 6 by a spring 84 of any suitable construction, located at any convenient point.

In order to insure positive opening of the jaws 60 at the proper point in the travel of the chain bearing all the parts just described, a triangular curved separator 86 may be, if desired, secured in position as shown in several of the figures, having inclined cam surfaces 87 terminating in a point 88 adapted to engage the sides 89 of a suitably formed recess 90 formed in the central top portion of each clamping jaw 60. In the particular machine here illustrated, the separator 86 is secured in position by the bolt 92 passing through a fixed part of the machine 93.

Cut transversely of the machine in member 24 are suitably placed and arranged dove-tail slots 94 within which slide dove-tail members 95 depending from the long horizontal plates 96 carrying yokes 97 in which are journaled a plurality of rollers 98. Rigidly attached to member 24 are parallel bars 99 in which are placed screws 100 adapted to adjustably bear upon the yokes 97 and thus force the rollers 98 inward toward the center of the machine, and against the outer vertical faces 101 of the gripping jaws 60, heretofore described. By adjusting the screws 100 in and out the pressure of the rollers 98 on the jaws 60 may be varied.

In the particular machine here illustrated, the shaft 33 is driven by any suitable power attached to a pulley 104 on a shaft 105 carrying a pinion 106 meshing with a gear 108 on shaft 33. Any other suitable means for driving this shaft may be applied without departing from this invention.

At the left hand or entrance end of the machine, as illustrated in the drawings, are placed two converging cam tracks 110 between which the gripping jaws 60 pass before entering the space between the rollers 98 for the purpose of closing the gripping jaws upon the tube 70 preparatory to the jaws being rigidly compressed by the rollers 98 on the tube, thus insuring their taking hold of the tube for the purpose of drawing, as will more fully appear hereafter.

Operation.

In the operation of the device, power is applied in the obvious manner so that the upper portion of the chain travels from left to right, as viewed in the figures. As the machine does operate, each successive pair of jaws 60 coming from the bottom of the chain, as viewed in Fig. 1, strikes the cam tracks 110 and are forced together against the action of their spring 84. From these cam tracks 110 the particular pair of gripping jaws 60 in question pass between the

rollers 98 and travel between them through the machine until after leaving the last pair of rollers 98, they engage the point 88 of the triangular cam member 86, which, as heretofore described, separates the jaws 60 notwithstanding any friction which may prevent spring 84 from separating them, as it should, whereupon such open pair of jaws pass down wheel 34 at the right hand end 10 of the machine, thence in open position along the bottom of the machine, and finally return to cam tracks 110 for the repetition of the operation just described. In feeding tubes or other articles to be drawn to the 15 machine, the free end of the tube is placed in proximity to the position of the jaws 60 as they are just ready to pass through the cam tracks 110, thus closing the jaws 60 upon the end of the tube. The tube is now 20 moved by hand in this position to the right into the machine until the first pair of rollers, and possibly the second pair, have gripped the jaws 60, whereupon the power in the chain device is sufficient to draw the 25 tube through the machine just as long as there is any tube to be drawn furnished by the manufacturing machine (not shown) placed at the left of the machine of this invention.

30 Special attention is called to the fact that in the preferred machine of this invention, the gripping jaws are fastened to the chain drive and are hinged thereto in such a way that they may be moved into and out of different relations with reference to the tube 35 or other product to be worked upon without interfering therewith, thus greatly reducing the number of parts heretofore required in devices of this class. Furthermore, the gripping jaws open automatically under spring 40 action which is rendered positive by the use of the cam device 86, and the pressure of the gripping jaws is adjustable through the use of the adjusting screws 100.

45 Owing to the fact that the series of rollers 98 through which the gripping jaws 60 pass is of considerable length and is nevertheless in rigid alignment, the device serves the useful function of practically straightening 50 slightly bent tubes passed through the device. By attaching the gripping mecha-

nism, practically directly to the power driven chain a very positive and efficient operation is obtained.

If it be desired to have this machine weld 55 the adjacent edges 120 of a lock joint tube, such as is shown in Fig. 5 or a butt joined tube, the machine may be designed with a suitable opening between the lines of contact of the jaws 60 for the insertion of the 60 flame from a brazing or welding torch without departing from this invention.

Having thus described my invention, what I claim as new and desire to secure by Letters Patent, is:

1. In a machine of the class described, a drive chain comprising pairs of primary links connected to intermediate links, pivotal means carried on an intermediate link and extending lengthwise of the chain, and 70 a pair of jaws pivoted upon said pivotal means adapted to swing toward each other to clamp the part to be drawn.

2. In a machine of the class described, a drive chain comprising pairs of primary links connected to intermediate links, pivotal means carried on an intermediate link and extending lengthwise of the chain, a pair of jaws pivoted upon said pivotal means adapted to swing toward each other to clamp the 75 part to be drawn and a block upon said intermediate link adjacent to the pivotal mechanism of said clamping jaws adapted to receive and support the clamping jaws and the bearings therefor, for the purposes set 80 forth.

3. As an article of manufacture for use in mechanism of the class described, a chain link 40 having near its ends space for pivot pins and having extending from one side 90 blocks 44 and 46 perforated to receive the pivot pins of a hinge, the block 46 being relatively large so as to receive and support the parts of a hinge device mounted upon such a pivot pin.

In witness whereof I hereunto subscribe my name this 23rd day of August A. D., 1916.

PATRICK H. FRIEL.
